UNITED STATES PATENT OFFICE.

LEROY S. PFOUTS, OF CANTON, OHIO, ASSIGNOR TO THE CANTON FOUNDRY
MACHINE COMPANY, OF SAME PLACE.

DESIGN FOR A FURNACE-CASING.

SPECIFICATION forming part of Design No. 30,638, dated April 25, 1899.

Application filed February 23, 1899. Serial No. 706,597. Term of patent 14 years.

To all whom it may concern:

Be it known that I, LEROY S. PFOUTS, a citizen of the United States, residing at Canton, Stark county, Ohio, have invented and produced a new and original Design for a Furnace-Casing, of which the following is a specification.

In the accompanying drawings, Figure 1 is a side elevation showing my design, and Fig. 2 is a front view of the same.

The design consists in the outline or configuration of the shell, and particularly in the undercut front D, provided with an over-

hanging part or ledge E. The main part of the casing is cylindrical above the part C, as at A and B.

I claim—

The design for a furnace-casing herein shown and described.

In testimony whereof I affix my signature in presence of two witnesses.

LEROY S. PFOUTS.

Witnesses:

GEO. W. JAHN,
C. H. VAN HORN.
